UNITED STATES PATENT OFFICE

JAMES BROPSON, OF CLEVELAND, OHIO

CLEANING DEVICE

Application filed July 26, 1929. Serial No. 381,214.

This invention relates to cleaning devices and has particular reference to devices of this character that are intended for removing obstructions in traps and toilet bowls.

5 The primary object of the present invention is to provide a cleaning device which shall be exceedingly simple in construction, inexpensive to manufacture and highly efficient in operation.

10 Another object is to provide a device of this character which shall be extremely flexible to enable it to be easily forced around bends in traps or other conduits and yet be stiff enough to enable it to readily remove the 15 obstruction.

With these and other objects in view, the invention may be stated to consist in the various novel features of construction and arrangement or combination, all of which will 20 be fully described hereinafter and pointed out in the appended claims.

In the drawings accompanying and forming part of the application, Fig. 1 is a plan view of a cleaning device constructed in accordance with my invention; Fig. 2 is a longitudinal sectional view through the same; Fig. 3 is a perspective view thereof showing the flexibility of the device; and Figs. 4 and 5 are respectively fragmentary views in side 25 elevation and plan illustrating a modification of the device.

A cleaning device constructed in accordance with my invention comprises a handle 10 having a kerf therein to receive a pair of 30 relatively thin flexible metal strips 11 and 12. These strips are fastened in the kerf of the handle in any suitable manner, as for example, by bolts 13 extending transversely therethrough.

40 The strips 11 and 12 project from the handle a suitable distance and at the opposite ends said strips are fastened to opposite sides of a head 14 by a rivet 15 or other suitable fastening means. As shown in Figs. 1 and 2, the head 14 is formed with a rounded nose portion 16 and barbed side portions 17, and I preferably recess each face of the head as indicated at 18 to receive the end portions of the strips 11 and 12.

45 Adjacent the head 14 I preferably apply

suitable oppositely disposed projections 20, 20 to the strips 11 and 12. These projections serve to expand or separate the strips adjacent the head 14, and also form barbs which are disposed in a plane at right angles to the 55 plane of the barbs 17.

In use, the head 14 is inserted in the trap, toilet bowl or other conduit to be cleared of an obstruction and the device forced therewith by pushing on handle 10. The rounded portion 16 of the head readily guides the device around bends without binding and the use of double strips 11 and 12 permits the device to readily conform to all turns and at the same time sufficient 65 rigidity is imparted to the device to allow it to be forced along the conduit without buckling. When the obstruction is encountered, it will be either forced through the conduit or engaged by the barbs 17 or 20 and 70 can be pulled back and removed, it being noted that these barbs are disposed in planes at right angles to each other thus insuring engagement of any obstruction encountered. By separating the strips adjacent the head, 75 sufficient rigidity is imparted at this end of the device to prevent the head from turning back on itself when the obstruction is encountered.

In Figs. 4 and 5 I have illustrated a slight 80 modification of the head portion. In this instance I form the head from a strip of metal 21 bent back upon itself and fastened at 22 to the strips 11 and 12. The metal strip 21 is preferably enlarged at 23 to define a 85 cylindrical nose portion to facilitate guiding it around bends in the conduit. In other respects the device is identical with that illustrated in Figs. 1-3 and is used in the identical manner.

90 What I claim is:

1. A cleaning device of the character described comprising a handle having a flexible element projecting therefrom and fitted at its opposite end with a head forming a continuation of said strip, said head having a flattened portion connected to said flexible element and an enlarged rounded portion disposed transversely of the longitudinal axis of the device said flattened portion being 100

formed with barbs projecting beyond the side edges of said flexible element.

2. A cleaning device of the character described comprising a handle, a pair of flexible elements projecting from said handle, and a head having a flattened portion secured to and between the opposite ends of said elements, the flattened portion of said head having a rounded nose portion.
- 10 3. A cleaning device of the character described comprising a handle, a pair of relatively thin flat metallic strips secured to said handle adjacent one end portion thereof, a head having a flattened portion secured between the opposite end portion of said strips, the flattened portion of said head having barbs projecting beyond the side edges of said strips and the forwardly projecting end thereof provided with a rounded nose portion.
- 15 4. A cleaning device of the character described comprising a handle, a pair of relatively thin flat metallic strips secured to said handle adjacent one end portion thereof, a rounded head secured between the opposite end portions of said strips and means adjacent said head for spreading said strips apart.

5. A cleaning device of the character described comprising a handle, a pair of relatively thin flat metallic strips secured to said handle adjacent one end portion thereof, a head secured to the opposite end portion of said strips, said head having a rounded nose portion and barbs projecting therefrom, and projections fastened to said strips adjacent said head, said projections serving to hold said strips separated adjacent said head.

In testimony whereof I affix my signature.
JAMES BROFSON.
